UNITED STATES PATENT OFFICE.

WILLIAM O. SINGER AND BERNARD J. SINGER, OF CRESSON, PENNSYLVANIA.

WRENCH.

1,382,938.

Specification of Letters Patent. Patented June 28, 1921.

Application filed August 28, 1920. Serial No. 406,625.

To all whom it may concern:

Be it known that we, WILLIAM O. SINGER and BERNARD J. SINGER, citizens of the United States, residing at Cresson, in the 5 county of Cambria and State of Pennsylvania, have invented certain new and useful Improvements in Wrenches, of which the following is a specification, reference being had to the accompanying drawings.

10 This invention relates to wrenches and particularly to a quick adjustable wrench.

An object of the invention is to provide a wrench of this character capable of being adjusted by the hand that holds the wrench.

15 Another object is to provide a wrench of this character having a novel adjusting sleeve disposed adjacent one end of the handle, said sleeve not only providing adjusting means for the wrench but serving as a handle 20 to permit the operator to obtain a firm grip.

Another object is to provide a wrench of this character wherein the adjustable jaw is slidable on the shank of the fixed jaw and is adjusted longitudinally of said shank 25 by means of a rotatable sleeve, said sleeve being prevented from longitudinal movement on the shank by the end portion thereof.

A still further object of the invention is 30 to provide a wrench of this character including a shank having its end reduced and threaded, said threaded end being adapted to receive a nut, said nut preventing disengagement of the slidable jaw and rotatable sleeve from the shank of the wrench.

35 With the above and other objects in view, the invention consists in the improved construction and arrangement of parts, to be hereinafter more particularly described, 40 fully claimed and illustrated in the accompanying drawing, in which:-

Figure 1 is a view partly in side elevation and partly in section of a wrench constructed in accordance with an embodiment of our 45 invention.

Fig. 2 is a view partly in rear elevation and partly in section of the structure as disclosed in Fig. 1, and

Fig. 3 is a sectional view taken substantially on the line 3—3 of Fig. 1.

Referring to the drawings, 5 designates a shank substantially rectangular in cross section, and having formed on one end a fixed jaw 6. The end 7 of the shank is reduced 55 and threaded as at 8, a collar 9 being formed between the end of the shank and the base

of the reduced portion. Two shoulders 10 and 11 are formed by the collar, the purpose of which will be hereinafter described.

A movable jaw 12 is provided, said jaw 60 including a tubular extension 13, a bore being formed in the jaw 12 and extension, the bore in the jaw and extension corresponding to the shape of the shank 5 so as to prevent lateral movement of the saw and extension 65 on the shank. The jaw 12 is slidably mounted on the shank, the exterior surface of the extension being threaded. It will be noted that there are no threaded or like means between the slidable jaw and the shank. 70

In order to permit adjustment of the slidable jaw, I provide a novel adjusting sleeve 14, said sleeve being internally threaded and adapted to receive the tubular extension 13 for telescopic movement. The end 15 is partially closed, said closed portion being provided with a central opening 16, corresponding in diameter to the exterior surface of the collar 9. By this means the end 15 engages the shoulder 10 so as to prevent longitudinal 80 movement of the sleeve on the shank 5.

To prevent disengagement of the movable jaw 12 and sleeve 14 from the shank I provide a nut member 17, one end of the nut coinciding with the end 15 of the sleeve 85 while the remainder of the nut tapers to the end of the threaded portion 8. In this way, the nut member forms a continuation of the sleeve so that a relatively large hand grip surface is provided, thereby permitting the 90 user to obtain a firm grip nearer the jaw of the wrench so that greater leverage is provided. It will be noted that the end of the nut 17 is limited in its movement by means of the shoulder 11 so that while it holds the 95 sleeve on the shank, it does not interfere with its rotary movement but instead provides a bearing surface for the end 15 of the sleeve. Should repairs or cleaning be necessary the nut 17 may be removed to permit disengagement of the sleeve 14 and movable jaw 12 from the shank 5 without the necessity of cutting rivets or loosening additional fastening means. 100

In use, the jaw 12 is slidable at all times 105 on the smooth shank 5 and as there are no threaded or like means between the shank and the jaw 12, the bracing action is not interfered with. When it is desired to adjust the wrench, the sleeve 14 is rotated 110 on the shank 5 thereby causing the threaded extension 13 to move inwardly or outwardly

of the sleeve 14 according to the adjustment desired. This is possible without causing the operator to move any adjusting means longitudinally of the shank and may be performed from the hand grip portion of the wrench and by the hand that holds the wrench, the threads permitting finest adjustment possible to be made and as the extension 13 is relatively long a considerable portion thereof is disposed practically at all times within the sleeve 14. This feature together with the bracing action of the shank eliminates stripping of the threads and permits the tightest nut to be readily moved. This operation is of course assisted by the enlarged hand gripping surface formed by the coöperation of the nut 17 and the relatively long sleeve 14.

From the foregoing it will be readily seen that this invention provides a novel form of wrench capable of being quickly adjusted without moving the adjusting means longitudinally of the shank, said adjusting means being retained on the wrench through the coöperation of the shoulders 10 and 11 and the nut 17, the nut permitting rotary movement of the sleeve but preventing accidental disengagement of the sleeve or sliding jaw from the wrench. In addition to this the sleeve and sliding jaw also assist to strengthen the wrench as it will be noted that the only portion of the shank exposed is that which extends between the jaws 5 and 6.

What is claimed is:—

35 1. A wrench of the character described comprising a shank, said shank having its end reduced and threaded, a shoulder formed at the base of the reduced portion,

a second shoulder formed between the reduced portion and the first mentioned shoulder, a slidable jaw including a threaded extension slidably mounted on the shank, an adjusting sleeve having a partially closed end adapted to receive the extension of the jaw, said partially closed end being also adapted to engage the first mentioned shoulder, and a nut threaded on said extension into engagement with the second mentioned shoulder, said second mentioned shoulder preventing longitudinal movement and permitting unrestricted rotary movement of the sleeve on the shank and extension of the slidable jaw.

2. A wrench of the character described comprising a shank, said shank having its end reduced and threaded, a shoulder formed at the base of the reduced portion, a second shoulder formed between the reduced portion and the first mentioned shoulder, a slidable jaw including a threaded extension slidably mounted on the shank, an adjusting sleeve having an annular flange projecting inwardly of one end and adapted to engage the first mentioned shoulder, and a nut threaded on said extension into engagement with the second mentioned shoulder, said nut coöperating with the first mentioned shoulder to provide a recess for the flange of the sleeve, whereby said sleeve may be rotated and prevented from longitudinal movement on the extension of the jaw and the end portion of the shank.

In testimony whereof we hereunto affix our signatures.

WILLIAM O. SINGER.
BERNARD J. SINGER.
